UNITED STATES PATENT OFFICE.

BRUNO V. NORDBERG, OF MILWAUKEE, WISCONSIN.

LINK-MOTION.

1,239,297.

Specification of Letters Patent.

Patented Sept. 4, 1917.

Application filed June 11, 1917. Serial No. 174,140.

To all whom it may concern:

Be it known that I, BRUNO V. NORDBERG, a citizen of the United States, residing at Milwaukee, in the county of Milwaukee and 5 State of Wisconsin, have invented a certain new and useful Improvement in Link-Motions, of which the following is a specification.

My present invention pertains to an improved link motion, the advantages of which 10 will hereinafter appear.

The main object of the invention is to construct and provide in a practical and satisfactory manner a link between an oscillating arm and another moving part, 15 which latter has a rectilinear motion, or moves in a line different from that of the point of attachment of the arm to said moving part.

20 When, for instance, a puppet valve or some other machine part that moves in a straight line has to be operated from an arm fulcrumed at some fixed point and attached to the valve stem at another point, 25 which latter point in the movement of the parts describes a curve, it has always been a difficult matter to provide a proper joint between said valve stem and arm which joint will have such freedom as to accommodate 30 itself to the curved path of movement of the connection between the arm and the stem and, at the same time, be free from lost motion and wear.

Ordinarily, some type of link or sliding 35 block is used for this purpose. A link is always the best mechanism, but when these links become very short, as will occur in nearly every case where a puppet valve is operated in the above-described manner, the 40 construction of such a link possesses great difficulties.

In the annexed drawings the invention is 45 illustrated as applied to a valve-stem deriving its motion from an oscillating lever, and wherein:

Figure 1 is a sectional elevation of the stem, the operating lever, and the interposed eccentric connection;

Fig. 2 a vertical sectional view; and

50 Fig. 3 a horizontal sectional view.

The valve-stem, denoted by 1, moves in a straight line, being supported and guided in suitable ways or guides 2. The stem is provided with an enlargement 3, bored out 55 to receive an eccentric 4, though as will be readily appreciated said enlargement may

be separately formed and attached to the stem.

The operating lever 5 is fulcrumed on a fixed shaft 6, the lever being broken away 60 at the right and the actuating mechanism therefor omitted. The other end of the lever is bifurcated and embraces the eccentric, being connected thereto by a through-bolt or pin 7, which makes a close fit within 65 a transverse bore formed in the eccentric above the center thereof.

As will be readily appreciated, a rocking motion of the lever will impart, through the eccentric, an endwise reciprocating move- 70 ment to the valve-stem 1.

The eccentricity of the eccentric, or the distance between the center of eccentric 4 and the center of the pin 7, denoted by α , see Fig. 1, then becomes the effective length 75 of the link. The relative motion between the center of pin 7, which passes through a curve α , with a radius y , and the rectilinear movement of the valve-stem 1 produces an oscillation of the eccentric 4 in the 80 enlargement or strap 3 to which it is fitted, and thus gives the mechanism freedom to operate.

It is evident that this mechanism is easy to construct and does not involve very many 85 accurate fits. Thus the arm or lever 5, fulcrumed on shaft 6, is held between two faces 8, 8^a of the support for the shaft, and the eccentric is fitted between the forked or bifurcated elements of the lever and is free 90 to oscillate with the enlargement 3 and about pin 7. It is not, however, necessary to provide accurate lateral alinement between the lever and the valve-stem, and the enlargement 3 may be made narrower than the ec- 95 centric to provide clearance between the stem and the bifurcated end of the lever.

All that is necessary is, that the eccentric fit properly in the bore of the valve-stem, that the pin 7 fit accurately in the eccentric, and 100 that the center line of the valve-stem and of the pin or shaft 6 shall be at right angles to each other, so that the center line of the valve-stem coincides with the plane of oscillation of pin 7. The arm and the valve- 105 stem can thus be guided freely, the former on its fulcrum pin or shaft 6, between the members 8 and 8^a , and the latter by its ways 2.

Having thus described my invention, what 110 I claim is:

1. In combination with a member recipro-

cable in a right line; an actuator therefor standing at substantially right angles to the line of movement of said member; and a connection between said member and actuator, comprising an eccentric carried by the member and connected with the actuator.

2. In combination with a valve-stem reciprocal in a right line; an included eccentric carried thereby; an actuating lever therefor, the center lines of said valve-stem and the lever standing at right angles to each other; and a pin connecting said lever to the eccentric.
15. 3. In combination with a valve-stem, reciprocal in a right line; an eccentric carried thereby; a lever fulcrumed to one side of the stem; and a pin extending through the eccentric to one side of the center thereof and connected to the adjacent end of the lever.

4. In combination with a valve-stem reciprocal in a right line; an eccentric carried thereby; a lever fulcrumed to one side of the eccentric, the center line of said lever and valve-stem standing at right angles to each other; and a pin extending through an opening formed in the eccentric and connected to the lever, the center of said pin being coincident with the point of crossing of the center lines of said stem and lever.

5. In combination with a member to be actuated, said member having a rectilinear movement; an actuating member having a swinging movement about a fixed fulcrum and standing at substantially right angles to the first-named member; and an eccentric connection between said members.

In testimony whereof I have signed my name to this specification.

BRUNO V. NORDBERG.
